ELECTRIC LIGHT FLASHER CASING

Noel J. Lituchy, New York, N. Y.

Application November 1, 1954, Serial No. 32,878

Term of patent 14 years

(Cl. D48—24)

FIG. 1

FIG. 2

FIG. 3

FIG. 4

Fig. 1 is a top view of an electric light flasher casing, showing my new design, the top and bottom being the same;

Fig. 2 is a front elevational view of the electric light flasher casing, the front and rear being the same;

Fig. 3 is a side elevational view looking at the left side of Fig. 1; and

Fig. 4 is a side elevational view looking at the right side of Fig. 1.

I claim:

The ornamental design for an electric light flasher casing, substantially as shown and described.
